UNITED STATES PATENT OFFICE.

MURRAY C. TUNISON, OF LOS ANGELES, CALIFORNIA, ASSIGNOR OF ONE-HALF TO CHARLES W. HARRISON, OF LOS ANGELES, CALIFORNIA.

EMERGENCY-TELEGRAPH.

No. 850,858.

Specification of Letters Patent.

Patented April 16, 1907.

Application filed July 27, 1905. Serial No. 271,401.

To all whom it may concern:

Be it known that I, MURRAY C. TUNISON, a citizen of the United States, residing at Los Angeles, in the county of Los Angeles and State of California, have invented a new and useful Emergency-Telegraph, of which the following is a specification.

This invention relates to a new form of telegraph instrument whereby any person is enabled to send a message, whether he understands telegraphy or not, and also whereby the message or messages may be sent from any point on a telegraph-line without the use of the customary station, operator, or instruments.

It is of the objects of this invention to provide a telegraph instrument very simple in construction and extremely easy to operate, to enable an unskilled person to send telegraphic communications independently of any knowledge of telegraphy to make an instrument of this character which may be comfortably carried in the pocket and which may be easily connected with a telegraph-line and operated quickly and readily when an emergency arises.

The invention comprises a device provided with one or more signals formed of insulating and conducting portions arranged in determined form and order, said conducting portions being adapted to form the terminal of a circuit, and a contact-point adapted to form the other terminal of the circuit and to make and break the circuit to transmit the signal when moved thereon.

In the preferred form the invention comprises an insulating character-plate, which may be formed of celluloid, gutta-percha, or other insulating material, indicating dots and dashes used to denote the different codes, characters, and letters used in telegraphic communications, and said plate is mounted over a conductor, which is adapted to be temporarily connected with a telegraph-line. A stylus or movable contact is provided, which when grounded and drawn along the signal-spaces comes in contact with said conductor, thereby when the conductor is connected with a telegraph-line causing the grounding of the electrical current from said line, which in turn makes all telegraph instruments on the line respond to the dots and dashes thus made.

The instrument is designed to be of espe-

cial value for use in testing-out electric lines and also for the use of track-inspectors, who will thereby be able to telegraph from any point on the line without the necessity of going to a station.

Another object is to so construct the instrument as to make it compact for carrying in the pocket and to provide in the same instrument both a transmitting and receiving instrument, and in this relation I provide a case stamped from sheet metal to form two tubes at its sides—one for holding a contact with a coil of wire around it and connected therewith for making connection with the telegraph-line, the other holding the stylus and grounding-needle and a coil of wire therefor. The stylus and the contact are preferably constructed as spools for holding their respective coils of wire. An outer case is also provided, as will hereinafter more fully appear.

A sounder may be mounted inside the outer case, so that the one instrument is provided with sending and receiving instruments.

The accompanying drawings illustrate the invention.

Figure 1 is a perspective view of the instrument as it appears when ready to be carried in the pocket, parts being broken away to show the contact and stylus. Fig. 2 is a perspective view of the instrument in use, parts of a telegraph and railroad line being shown. Fig. 3 is an enlarged section on line $x^3 x^3$, Fig. 1, and shows diagrammatically the connections when the instrument is in use. Fig. 4 is a section on line $x^4 x^4$, Fig. 3, showing the sounder. Fig. 5 is an enlarged fragmental section on line $x^5 x^5$, Fig. 1, and shows the relation between the guide and character plates. Fig. 6 is an enlarged perspective view of a portion of the guide and character plates, showing the relation between the same. Fig. 7 is an enlarged broken view of the contact with its coil of wire.

1 is a conductor formed as a sheet-metal case turned at the sides and bottom to form grooves 2. At either side are tubes 3 and 4, closed at their bottoms and open at their tops. On the inside of tube 3 is an insulating-tube 5, which in turn surrounds a metallic tube 6. Inside the tube 6 contact 7 is held, making contact with the tube by the spring-contacts 8 at its top. At the bottom of the

contact is a collar 9, which forms, with the contacts 8 and the spindle 10, a spool on which conducting-wire 11 is wound. The head 12 of the spool extends over and closes the mouth of tube 3, so that the spool of wire may be withdrawn easily. When packed for the pocket, tube 4 carries another conductor in the form of a conducting-stylus 13, which has on it a spool of wire 14, the free end of the wire being connected to a conducting-needle 15, also contained in tube 4. On the back of the case is mounted a telegraph-sounder 16, provided with flat coils 17, armature 18, and adjusting-springs 19 and screw 20. Armature 18 is preferably constructed of aluminium with an iron face *a* attached to it. Coils 17 are connected by wire 21 to tube 6 and by wire 22 to the case of the instrument. The sending appliance comprises a stylus and a device comprising a conductor and an insulator provided with interstices through which the stylus can reach the conductor. Such device may comprise a character-plate 24, guide-plate 25, and cover-plate 26, which are held against the case in grooves 2. Character-plate 24 has on it characters *b* made up of dots and dashes to represent the different characters and letters of the alphabet or code to be used. One other character is made up for a call and is placed above or beside the letter or code characters. Short slots 27 are open through the character-plate to represent the dots and long slots 28 to represent the dashes. The dots and dashes of each character are arranged in a row, and means are arranged to guide the stylus along the line of slots forming such characters. The character-plate being of insulating material, the stylus can make contact with the plate only when it is projecting through one of the slots. Directly over the dots and dashes of the character-plate are slots 29 in the guide-plate 25, which form the guide for the stylus and are of sufficient length to allow a starting and stopping point for the stylus before and after passing over the dots and dashes of the character-plate.

In practical use the stylus following along the slots of the desired character and in the slots of the guide-plate is forced to traverse all of the slots of the character-plate in that line. The guide-slots preferably have an enlargement. A removable cover-plate 26 is provided as a protection to the guide and character plates when the instrument is not in use.

When the use of the instrument is required, contact 7 is withdrawn and wire 11 is wound and thrown over the line-wire 30, as shown in Fig. 2. Stylus 13 is withdrawn and needle 15 is ground as on rail 31. The call is then given by drawing the stylus along the guide-slot of the call character *c*. When the call has been made the desired number of

timies to get attention, the message will then be sent by drawing the stylus along the guide-slots for the required characters in the appropriate sequence. While the stylus is in contact with the conductor-plate 1, a circuit will be formed from battery 32, through the line-wire 30, wire 11, contact 7, tube 6, wire 21, coils 17, wire 22, case 1, stylus 13, wire 14, and ground 33 formed by the needle, back to the battery. When the message has been sent and one is to be received, the stylus is grounded on the case and the message may be read off the sounder.

While I deem it advisable to ordinarily provide the instrument with a sounder, it is to be understood that in some instances the sounder may be omitted and the instrument used simply as a transmitting device.

The character-plate and guide are practically a unit and may be formed of a single thickness of celluloid, gutta-percha, or other suitable insulating material stamped or pressed to form the guide and signal slots 29 and 27.

To operate, the person using the instrument may draw the stylus or movable contact in succession across the signals of the character-plate to form the letters, words, and phrases he wishes to send.

It will be understood that any person, no matter how ignorant of telegraphy, may send a message. I propose to especially use my emergency-telegraph on railroad and telegraph lines. Under my system every trainman may be provided with an instrument to be used in case of emergency, when one of the wires carried in the instrument will be thrown over the telegraph-line and the other connected to the ground.

It will be seen that the construction shown makes a very compact and convenient form for handling. However, the instrument may be made in various forms without departing from the spirit of my invention.

What I claim is—

1. A case provided at either side with receptacles for coils of wire, a character-plate adapted to fit between and be retained by said receptacles, a stylus connected with one coil of wire, said coil being removable from its receptacle for the purpose of grounding, and a contact carrying a second coil of wire for making connections between said case and telegraph-line.

2. A conductor consisting of a sheet-metal case turned at the sides and bottom to form grooves, tubes at either side of said case, an insulating-tube inside of one of said tubes, a metallic tube inside of said insulating-tube, spring-contacts within said metallic tube, a wire coil connected with said contacts, a character-plate, and a stylus with a wire for grounding and a needle adapted to operatively engage said character-plate.

3. A case, a sounder secured to and in-

closed by said case, a character-plate extending across one side of said case, a conductor beneath said character-plate, receptacles for coils of wire within said case, and a stylus 5 adapted to operatively engage said character-plate, said stylus and conductor being suitably wired to form a circuit.

4. A case forming one terminal of a telegraph-line, a telegraph-sounder mounted on 10 and connected in series with said case, an insulating character-plate, and a stylus forming the second terminal and adapted to contact with the case through the character-plate.

5. A case with receptacles for coils of wire 15 and provided with grooves for the reception of a character-plate, a character-plate, a stylus carrying and connected with one coil of wire, the other end of which is grounded, and a contact carrying a second coil of wire 20 connected to said case and a telegraph-line.

In testimony whereof I have hereunto set my hand, at Los Angeles, California, this 19th day of July, 1905.

MURRAY C. TUNISON.

In presence of—

JAMES R. TOWNSEND,
JULIA TOWNSEND.
